CLAIM

The ornamental design for a combined stereoscope and slide, as shown and described.

DESCRIPTION

FIG. 1 is a perspective view of a combined stereoscope and slide showing my new design;

FIG. 2 is an exploded view showing assembly of the stereoscope;

FIG. 3 is an enlarged side elevational view thereof, with the slide inserted into the stereoscope, the undisclosed opposite side being identical;

FIG. 4 is a perspective view as seen from the bottom of FIG. 1, and,

FIG. 5 is an enlarged elevational view as seen from the rear of FIG. 1.
